UNITED STATES PATENT OFFICE.

JOHN H. BREWER AND JOHN CHARLES, OF HAGERSTOWN, MARYLAND.

MECHANICAL MOVEMENT.

1,170,871.

Specification of Letters Patent.

Patented Feb. 8, 1916.

Application filed September 15, 1914. Serial No. 861,854.

To all whom it may concern:

Be it known that we, JOHN H. BREWER and JOHN CHARLES, citizens of the United States, residing at Hagerstown, in the county of Washington and State of Maryland, have invented certain new and useful Improvements in Mechanical Movements, of which the following is a specification.

Our invention relates to new and useful improvements in a mechanical movement, and has for its primary object the provision of a movement particularly adapted for lifting jacks, presses, or similar devices in which it is desired to secure a vertical or longitudinal movement of an element.

A further object is the arrangement of the several parts, whereby a movement may be given in either direction.

A still further object is the construction of such a mechanical movement which is easily operated and may be easily attached.

With these and other objects in view the invention consists in the novel details of construction and arrangement of parts which will be more clearly understood from the following description and drawings, in which,

Figure 1 is a view in side elevation. Fig. 2 is a section on the line 2—2 of Fig. 1. Fig. 3 is a vertical section. Fig. 4 is a detail of the operating pawl. Fig. 5 is a detail of one of the side bearing plates. Fig. 6 is a detail of the adjusting shaft, and Fig. 7 is a detail of the locking pawl.

In the drawings, we have illustrated the mechanical movement as applied to a lifting jack but we desire it understood that we do not limit ourselves to this particular use, and as stated above, the movement may be used on any device where it is desired to impart a vertical or longitudinal movement to an element.

The numeral 1 indicates the ordinary form of lifting jack standard having the base 2 upon which the standard rests. Slidably mounted within the standard 1 is the lifting bar 3 having the concaved seat 4 on the top thereof and the foot 5 extending from the side at the bottom. The bar 3 is provided on one edge with a plurality of teeth 6 which are adapted to be engaged by the lifting element for raising the bar.

The mechanical movement in which our invention resides comprises two plates 7 one of which is secured to each side of the standard by means of a shaft 8 extending through

the plates and sides of the standard. The plates 7 are provided with the extensions or ears 9 the purpose of which will be presently described. A lifting pawl 10 is pivotally connected to the plates 7 by means of the extending arms 11 and is provided with the ears 12 to which is pivotally connected an operating lever 13, at 14. This operating lever is provided with a plurality of perforations 15, the purpose of which will be presently described. Links 16 are connected to the operating lever 13 and to the ears 9 of the plates 7 and a shaft 17 forms the connecting means for the links 16 to the ears 9 of the plates 7. This shaft 17 is provided with a bifurcated extension 18 and a rod 19 is secured within the bifurcated portion. A screw threaded rod 20 passes through one end of the shaft 17 and is adapted to engage 75 a curved plate 21 on one of the plates 7. The purpose of this screw threaded rod is for releasing the shaft whereby it may be rotated for changing the position of several elements for reversing the movement of the 80 operating parts. This will be more clearly brought out later as the description proceeds. A pawl 22 is pivotally connected to the top of the standard 1 and is adapted to engage the teeth 6 on the bar 3. A bolt 23 passes through an ear 24 on the pawl and secured to the bolt 23 and to the bar 19 in the bifurcated portion 18 of the shaft 17 is a connecting wire 25 having the spring 26 formed midway the ends thereof. 90

When the several parts of the device are in the position shown in Figs. 1 and 3 of the drawings, the bar 3 is adapted to be raised by the operation of the lever 13. To raise the bar the lever 13 is raised thereby 95 releasing the lifting pawl 10 from the teeth 6 and allowing the pawl to drop downward toward the next lower tooth. Then when the lever is depressed or lowered the pawl engages the tooth and will thereby raise the 100 bar 3. When the lever 13 is raised all of the parts assume the position shown in dotted lines and it will be noted that the wire 25 securely holds the pawl 22 in engagement with the teeth. When it is desired to lower the bar 3 the screw bolt 20 is released from the curved plate 21 and the shaft rotated. This brings the screw bolt 20 into the position shown in dotted lines in Fig. 1 of the 105 drawings, and throws the bifurcated extension 18 into the position shown in dotted lines, Fig. 3. When in this position when

the lever 13 is lowered it will draw the pawl 22 away from the teeth 6 and the pawl 10 on the lever will engage the teeth 6 and when the lever is raised it will allow the bar 3 to drop so that the pawl 22 will engage the next higher tooth. In lowering the bar it will be understood that the movement of the lever is opposite from that in raising the bar. In raising the bar the pawl 10 engages under the teeth and by pulling down on the lever the bar is raised. In lowering the bar the lever is lowered so as to engage the top of one of the teeth and as the lever is raised forces down the tooth and lowers the bar. While engaging the lever with the teeth the pawl 22 will engage and hold the bar in position. As the pawl 10 is brought into contact with the teeth the lever being in its lowermost position the pawl 22 will be drawn from the teeth by means of the wire 25. As the lever is raised to lower the bar the wire 25 will again force the pawl 22 into engagement with the teeth, thereby locking the bar until the lever is again in position for lowering the same. In order to secure various adjustments for operating the lever the perforations 15 are provided in the lever and the links 16 may be connected by means of the pin passing through any of the perforations.

Having fully described the invention what we claim as new and desire to secure by Letters Patent is:

1. In a mechanical movement the combination with a guide and a toothed bar operating therein, of a plate mounted in the guide, a link connected to said plate, an operating lever supported by said link, a pawl pivotally connected to said plate and lever adapted to engage the toothed bar.

2. In a mechanical movement the combination with a guide and toothed bar operating therein, of a plate secured to the guide, a link connected to said plate, an operating lever supported by said link, a pawl connected to the plate and lever and engaging with the toothed bar, a rotatable shaft secured to said plate and link, a second pawl adapted to engage the toothed bar, and means connecting the second pawl and rotatable shaft.

3. In a mechanical movement, the combination with a guide and a toothed bar operating therein, a plate mounted in said guide, a link secured to the plate, an operating lever supported by said link, a pawl pivotally connected to the plate and lever engaging with the toothed bar, a second pawl adapted to engage with the toothed bar, a rotatable shaft secured to the plate and link, means for adjusting the rotatable shaft, and means connecting the second pawl and rotatable shaft.

4. In a mechanical movement the combination with a guide and a toothed bar operating therein, of a plate secured to the guide,

a link secured to the plate, an operating lever supported by said link, a pawl pivotally connected to the plate and lever and engaging the toothed bar, a second pawl engaging the toothed bar, a rotatable shaft connected to the plate and link, means for adjusting the said shaft, and a flexible connection between the rotatable shaft and second pawl.

5. In a mechanical movement the combination with a guide and a toothed bar operating in the guide, of a plate mounted in the guide, a pawl pivotally connected to the plate, a lever pivotally connected to the pawl, a link connecting the plate and lever, a second pawl pivotally connected to the guide and adapted to engage the toothed bar, and means connecting the lever and second mentioned pawl, said means consisting of the said link and a flexible member.

6. In a mechanical movement the combination with a guide and a toothed bar slidably mounted in the guide, of a plate pivotally secured to the guide, a pawl pivotally connected to the plate, a lever pivotally connected to the pawl, a link connecting the plate and lever, a rotatable shaft secured to the link and plate, means for rotating the shaft, a second pawl secured to the guide, and means connecting the second pawl and rotatable shaft.

7. In a mechanical movement the combination with a guide and a toothed bar slidable in the guide, of a plate pivotally mounted in the guide, a pawl pivotally connected to the plate and adapted to engage the toothed bar, a lever pivotally connected to the pawl, a link connecting the lever and plate, a rotatable shaft connected to the link and plate and provided with a bifurcated extension, a threaded bolt passing through the shaft and engaging the plate, a second pawl pivotally connected to the guide and adapted to engage the bar, and means connecting the second pawl and bifurcated extension on the shaft.

8. In a mechanical movement the combination with a guide and a toothed bar slidable therein, of a plate pivotally mounted within the guide, a curved projection secured on the plate, a pawl pivotally connected to the plate, a lever pivotally connected to the pawl, a link connecting the plate and lever, a rotatable shaft secured to the link and plate, a threaded bolt passing through the shaft and adapted to engage the curved projection on the plate, a second pawl pivotally connected to the guide and adapted to engage the toothed bar, and flexible means connecting the second pawl and rotatable shaft.

9. In a mechanical movement the combination with a guide and a toothed bar slidable therein, of a plate pivotally mounted within the guide, a curved projection on the plate, a pawl pivotally connected to the

plate, a lever provided with a plurality of perforations pivotally connected to the pawl, a link connected to the lever and plate, a shaft rotatably connected to the plate, a threaded bolt passing through the shaft and adapted to engage the projection on the plate, a second pawl pivotally connected to the guide and adapted to engage the bar, and a flexible connection connected to the 10 second pawl and rotatable shaft.

10. In a mechanical movement the combination with a guide and a toothed bar slideable therein, a pair of plates pivotally mounted within the guide, a pawl pivotally mounted between the plates, a lever pivotally connected to the pawl, a pair of links connecting the lever and plates, a shaft rotatably mounted between the plates, a second pawl pivotally connected to the guide, 15 and flexible means connecting the said second pawl and rotatable shaft.

11. In a mechanical movement the combination with a guide and a toothed bar slideable therein, a pair of plates pivotally mounted within the guide, a pawl pivotally mounted between the plates, a lever pivotally connected to the pawl, a pair of links connecting the lever and plates, a shaft rotatably mounted between the plates, a second pawl pivotally connected to the guide, and flexible means connecting the said second pawl and rotatable shaft.

11. In a mechanical movement the combination with a guide and a toothed bar slideable therein, a pair of plates pivotally mounted within the guide, a pawl pivotally mounted between the plates, a lever pivotally connected to the pawl, a pair of links connecting the lever and plates, a shaft rotatably mounted between the plates, a second pawl pivotally connected to the guide, and flexible means connecting the said second pawl and rotatable shaft.

able therein, of a pair of plates mounted in the guide, curved projections secured to 25 the plates, a pawl pivotally connected between the plates and adapted to engage the toothed bar, a lever pivotally connected to the pawl, a pair of links connecting the lever and plates, a shaft having a bifurcated extension rotatably mounted between the plates, a threaded bolt passing through the shaft and adapted to engage the curved projection on the plate, a second pawl pivotally connected to the guide and adapted to engage the toothed bar, and a flexible connection between the second pawl and bifurcated extension of the rotatable shaft. 30
